CONVERTIBLE GLIDER

William I. Smith, Perrysburg, Ohio, assignor to
The Hettrick Manufacturing Company, Toledo,
Ohio, a corporation of Ohio

Application September 13, 1939, Serial No. 294,714

3 Claims. (Cl. 5—37)

This invention relates to articles of furniture but particularly, although not exclusively, to gliders which are adapted to be converted for use as a bed.

An object is to produce an article of furniture of the above character equipped with back and seat structures in which the back can be moved to a position substantially in alignment with the seat and the spring cushion on the seat can be anchored or so connected to the back structure as to militate against sagging so that a more comfortable arrangement is produced and in which there is no abrupt change in the spring action between the back structure and seat cushion, it being understood that ordinarily in structures of this character, the seat is provided with a relatively soft resilient cushion but the back structure, although being provided with a cushion, does not have as soft or flexible arrangement.

Another object is to produce a glider equipped with relatively yielding and flexible seat cushioning springs and a back structure which can be moved to form with the seat a bed, means being provided for suitably connecting the back and seat structure when in bed-forming position to militate against a "soft spot" in the region between the back and seat structures.

Other objects and advantages of the invention will hereinafter appear and for purposes of illustration but not of limitation, an embodiment of the invention is shown on the accompanying drawings in which

Figure 1 is a front perspective view of a glider embodying the invention, the cushion pads being removed;

Figure 2 is an enlarged front perspective view of a portion of the glider shown in Figure 1 and with the back structure swung down into bed-forming position but with the back structure disconnected from the seat springs;

Figure 3 is a view similar to Figure 2 but showing the seat spring unit attached to the back structure;

Figure 4 is an enlarged sectional view substantially on the line 4—4 of Figure 2; and

Figure 5 is an enlarged sectional view substantially on the line 5—5 of Figure 3.

The illustrated embodiment of the invention comprises a glider having a supporting frame consisting of a pair of U-shaped rods 10 and 11, the ends of the U's being turned upwardly and engaged by upright sheet metal supporting panels 12 which are socketed at their opposite ends to receive the end portion of the tubes 10 and 11. The particular construction of the sup-

porting frame forms no part of the present invention, the same being fully shown and described in the patent to Louis Vavrik, No. 2,123,345, dated July 12, 1938.

Suspended for to and fro swinging movements between the uprights 12 is a seat structure generally indicated at S. As shown, a pair of hangers 13 are pivoted respectively at their upper ends to the end frames 12 and at their lower ends to legs 14 depending from the seat frame S. The seat frame S is made up of a rectangular supporting frame 15 of angle iron. Supported on the frame 15 in any suitable or well-known manner is a coil spring arrangement consisting of a series of coil springs 16 carried by cross-cross wires 17 hooked onto the frame 15, a metal slat 18 reenforcing the structure. The upper ends of the series of coil springs is enclosed by a relatively heavy wire frame 19 to which the adjacent springs are anchored, similar criss-cross wires serving to retain the springs in the desired position. It will be understood that one or more fabric seat pads are placed upon the coil spring structure in the usual manner.

Suitably fixed to each rear corner portion of the seat frame 15 is an upwardly and rearwardly inclined bracket arm 20 and pivotally connected to the bracket arms are the lower end portions of a back frame generally indicated at B. The back structure B is made up of a rectangular frame 21 of approximately the same length as the seat frame 15 and also constructed of angle iron. The frame 21 carries a cushioning structure which, in this instance, is made up of a plurality of horizontally extending straps 22 which are connected by coil springs 23 to each end of the frame 21. A strap 24 is disposed intermediate the ends of the frame 21 and is disposed beneath the straps 22 for reenforcing them. On the opposite side of the straps 22 are transverse straps 25 which are connected by coil springs 26 to the outer side of the frame 21.

Normally the back structure B is supported in upwardly inclined position, indicated in Figure 1, by studs 27 on the ends of the frame 21 which are selectively engageable in holes 28 formed in a rearwardly extending bracket plate 29. The bracket plate 29 at each end is carried by an arm rest structure 30 which is suitably secured to the seat frame 15 so as to move with it, as will be readily understood by those skilled in this art. It will be manifest that the back structure B can be freed from the bracket plates 29 by merely flexing the latter outwardly away from the adjacent stud 27. Thereupon, the back structure may

be swung downwardly into a position substantially in alignment with the coil spring series carried by the seat frame 15. In order to support the back structure in its downward position, a 5 pair of legs 31 pivoted to the outer side of the back frame 21 can be swung downwardly to the position indicated in Figures 2 and 3 to provide a support therefor.

When the back structure B is swung downwardly to the position shown on Figures 2 and 3, it is in bed-forming position and cooperates with the spring cushion on the seat frame to provide a double bed which may receive the cushions (not shown) normally resting against the back structure B and on the seat cushion, or may receive a mattress of a size sufficient to cover both the back and seat structures.

As shown particularly on Figure 4, when the back structure is swung downwardly to bed-forming position, the coil spring cushion on the seat frame 15 is slightly spaced laterally and vertically from the back frame. It will also be observed that the spring arrangement making up the seat cushion is more flexible and relatively 25 softer than the cushion on the back frame. Consequently, unless some provision is made to compensate for these differences in flexibility, the structure would not be particularly comfortable for use as a bed, because the center part in the 30 region of the inner side of the back structure B and the adjacent seat spring arrangement would provide, on the one hand, a relatively hard and uncomfortable ridge formed by the edge of the back frame and, on the other hand, a relatively 35 soft and yieldable seat spring structure. To overcome this difficulty, a plurality of hooks 32 are riveted at spaced intervals to the inner side of the back structure B, each hook projecting beyond the side of the back structure, and these 40 hooks are arranged to receive the adjacent length of the wire frame 19 of the seat spring assembly. As indicated in Figure 4, when the back structure is in its horizontal position, the frame 19 is spaced from the hook members but by lifting 45 up on the frame 19 and slightly elongating the adjacent coil springs 16, the frame may be moved into engagement with the hooks 32 thereby bringing the upper surfaces of the coil springs 16 substantially into alignment with the back frame B. In this manner, the flexibility of the bed 50 formed in this manner is more nearly uniform and the abrupt demarcation from a relatively rigid to a relatively flexible surface is considerably lessened. This provides a much more comfortable supporting surface and materially 55 reduces objections heretofore inherent in a convertible glider of this character. When the back frame B is swung upwardly to its normal position to convert the structure again into use as a glider, it will be apparent from an examination 60 of Figure 5 that the hooks 32 will be swung downwardly and rearwardly about an arc defined by the pivotal connection between the back

frame and the supporting brackets 20. This results in an automatic release of the wire frame or border wire 19 so that the spring structure then assumes its original position. It will then be apparent that upon again connecting the 5 studs 27 to the bracket plate 29, the back is then in position for use as a glider.

It is to be understood that numerous changes in details of construction, arrangement and operation may be effected without departing from 10 the spirit of the invention especially as defined in the appended claims.

What I claim is:

1. An article of furniture of the type set forth, including a supporting frame, a seat structure 15 mounted on the frame and including an assembly of vertically arranged coiled springs, means interconnecting the top coils of the spring assembly, a bar-like member at the rear of the assembly and disposed in the plane of the tops of the 20 coils and connected to adjacent top coils, vertically extending members connected to the frame, a back member pivotally connected to the vertical members so as to be movable in one position to lie in a substantially horizontal plane, and 25 means rigid with the lower edge of the back member and with which said bar-like member is engageable when the back element is in horizontal position so as to bring and hold the top surface of the spring assembly at the rear thereof, close to and substantially in the plane of the 30 back member, and means to support the back member against downward movement when in said horizontal position.

2. An article of furniture in accordance with 35 claim 1, wherein the means rigid with the back member consist of hooks, formed so that when the back member is moved to occupy a vertical position, the hooks will be automatically disengaged from the bar-like member of the seat structure.

3. An article of furniture of the type set forth 40 including a supporting frame, a seat structure mounted on the frame, and including an assembly of vertically arranged coil springs, means interconnecting the top coils of the spring assembly, an element at the rear of the assembly and disposed in the plane of the top coils and connected to adjacent top coils, vertically extending members connected to the frame, a back element 45 pivotally connected to the vertical members so as to be movable in one position to lie in a substantially horizontal plane, means rigid with one of said elements and movably engageable with the other thereof, when the back member is in horizontal position to bring and hold the top surface of the spring assembly at the rear thereof, close to and substantially in the plane of the 50 back element, and means to support the back element against downward movement when in said horizontal position.

WILLIAM I. SMITH.
